W. WURDACK

SCREW DRIVER MACHINE

Filed Sept. 3, 1921

UNITED STATES PATENT OFFICE.

WILLIAM WURDACK, OF ST. LOUIS, MISSOURI.

SCREW-DRIVER MACHINE.

Application filed September 3, 1921. Serial No. 498,381.

To all whom it may concern:

Be it known that I, WILLIAM WURDACK, a citizen of the United States, residing at the city of St. Louis, State of Missouri, have invented a certain new and useful Improvement in Screw-Driver Machines, of which the following is a specification, reference being had to the accompanying drawing, forming a part thereof.

10 This invention relates generally to screw-driver machines, and, more particularly, to a certain new and useful improvement in screw-driver machines of the automatic power driven type, the principal object of 15 my present invention being to provide a machine of the class stated which may be economically manufactured, which is compact and durable in form and construction, in which manual holding of the screw to 20 be driven is entirely obviated, and by which the held screw is quickly and efficiently driven to its seat in the work being operated upon.

With the above and other objects in view, 25 my present invention resides in the novel features of form, construction, arrangement, and combination of parts hereinafter described and afterwards pointed out in the claims.

30 In the accompanying drawing,

Figure 1 is a longitudinal sectional elevation of a screw driver machine constructed in accordance with and embodying my invention;

35 Figure 2 is a front elevational view of the machine;

Figure 3 is an enlarged sectional elevation of the machine taken approximately on the line 3—3, Figure 1, showing fragmentally 40 the magnetic screw-holding means of the machine; and

45 Figure 4 is an enlarged perspective view of a portion, approximately one-half, of the pole-pieces of the magnetic screw-holding means.

Referring now more in detail to the said drawing, which illustrates a practical embodiment of my invention and in which like reference-characters refer to like parts throughout the several views, the base of the machine is preferably in the form of an open approximately rectangular frame 1 adapted, in use, to be bolted or otherwise fixed to a work-table or other suitable support, not shown. The frame 1 is formed

with journal-box sections or bearings 2—2, mounted for rotation in which is a shaft 3. Surmounting the base-frame 1 and rigidly attached thereto by bolts or the like 4, is a cap 5 having the complementing journal-box sections or shaft-bearings 6.

Loosely mounted on the shaft 3, is a pulley 7 adapted for driven connection by means of a belt or the like with a suitable source of power; and disposed upon shaft 3 forwardly of the pulley 7, is a clutch-member 8. The clutch-member 8 is rigidly fixed, as by a pin 9, to rotate with shaft 3, and its hub 10 preferably abuts for rotary movement against a wall of the machine-housing formed by the base-frame 1 and cap 5 to hold the shaft 3 against longitudinal or axial movement in one direction.

I may state here that shaft 3 is suitably held from axial movement in the other direction as by a plate or disk 11 fixed to the machine-housing over the rear end of the shaft, that for the lubrication of the shaft 3 in the boxes 2, I provide the oil-holes 12—12, and for the lubrication of the pulley 7 I provide in shaft 3 communicating longitudinal and cross ducts 13 and 14, respectively, leading from one journal box 2 to the pulley, as best seen in Figure 1.

The clutch-member 8 is preferably faced with a disk 15 of leather or other suitable material, and disposed upon shaft 3 with its opposite ends abutting against the rear end of a hub-extension 16 of the pulley 7 and a ring 17 fixed on the shaft 3, as best seen in Figure 1, is an extensible coiled spring 18 for yieldingly maintaining or holding the pulley 7 at its forward face in frictional driving engagement with the face 15 of clutch-member 8.

The main shaft 3 projects forwardly beyond the machine-housing, and formed in its so projecting end is a threaded socket 19, in which is firmly seated a screw-driver bit or tool 20. And loosely fitted over the projecting end of shaft 3 to slide axially thereupon, is a block 21, which is yieldingly actuated in a forward direction by a spring 22 coiled about the shaft 3 and interposed between the block 21 and the forward end shaft-bearing formed by the complementing journal-box members or sections 2 and 5, as seen in Figure 1, the axial movement of the block 21 in such forward direction

being limited adjustably by a stop in the form of a rod 23 fixed at its rear end to the machine frame and projecting forwardly through a slot 24 in block 21 and at its forward end carrying a nut 25 adapted for adjustable engagement with the block 21, as illustrated in Figures 1 and 2. Due also to the straddling engagement of the rod 23 by the movable block 21 at its slot or bifurcation 24, the block 21 is held against movement other than axial on and relatively to the shaft 3 and its carried bit or tool 20.

The block 21 constitutes the supporting part of the screw-holding means proper, which includes a permanent magnet 26 preferably of the horse-shoe type and pole-pieces 27. The poles 27, as shown, are made as two complementing parts which are fixed to the legs of the magnet 26 by means of a bar 28 and screws 29 extending through the bar 28 and the pole elements 27 into the legs of the magnet, as clearly illustrated in Figure 3, the adjacent ends of the pole pieces 27 being suitably spaced one from the other to provide a magnetic gap and also shaped to provide not only for lengthwise rotary working movement therebetween of the tool or bit 20, but also a seat, as at 30, for the head of the screw 31, shown in dotted lines in Figure 1, to be driven.

The magnet 26 and its poles 27 are disposed approximately flatwise upon the block 21 with the screw-seat 30 in operative alignment and registration with the bit or tool 20, and are detachably or renewably fixed in such position by means of a filler block 32 resting upon the block 21 between the legs of magnet 26 and a face-plate 33 which overlaps the magnet legs, as well as also the pole-pieces 27 and their securing-bar 28, securing or fastening screws 34 being passed through the plate 33 and block 32 into the supporting-block 21. By preference, the face-plate 33 is additionally secured as by a screw 35 which seats in the hub of the block 21, as seen in Figure 1; and I may add that the pole elements 27 are held magnetically insulated one from the other by means of interposed tongues 36 and 37 on the bar 28 and filler-block 31, the insulation further including the making of the supporting-block 21, the bar 28, the filler 32, the face-plate 33, and the tongues 36 and 37 of brass.

In Figure 1, I have shown by dotted lines the screw 31 magnetically held at its head to the seat 30 by the poles 27 and a piece of work into which the screw is to be driven.

In operation, presuming the pulley 7 to be belted to, and being rotated by, a suitable source of power, and the shaft 3 and its carried tool 20 to be consequently also rotated under the yielding-frictional engagement between the pulley 7 and clutch-member 8. A screw 31 is now manually or other-

wise placed with its head upon seat 30 and 65 between the pole-pieces 27, which head bridges the pole-pieces and hence the screw is magnetically held. The work with a screw-seat is then forced toward the held screw 31, and in such movement or travel 70 the work, the block 21 is moved rearwardly against the tension of spring 22, the held screw being thereby carried into engagement with the rotating driver or tool 20, whose point, after finding the nick or groove 75 in the screw-head, turns the screw into the seat in the work. The work and screw are held against the tool 20 until the screw is fully seated, at which time rotation of the tool is stopped and breakage of parts obviated, which act is permitted by reason of 80 relative slipping between the clutch 8 and pulley 7. After manual pressure is relieved from the work, the spring 22 restores the block 21 and its carried parts to starting or 85 normal position as determined by the stop-nut 25.

From actual use, I have found my new machine to be exceedingly fast and efficient and to effect a considerable saving in time 90 and labor.

I am aware that changes in the form, construction, arrangement, and combination of the several parts of my new screw-driver machine may be made and substituted for 95 those herein shown and described without departing from the nature and principle of my invention.

Having thus described my invention what I claim and desire to secure by Letters Pat- 100 ent is:

1. A machine of the class described including a rotary screw-driver and means for 105 rotarily actuating the same, in combination with means comprising a magnet having an apertured seat-providing pole-piece for magnetically holding a screw in position for driven engagement by the screw-driver.

2. A machine of the class described including a rotary screw-driver and means for 110 rotarily actuating the same, in combination with means for magnetically holding a screw to be driven, said means comprising a magnet having an apertured seat-providing pole-piece and being shiftable toward the screw-driver for driven engagement with the held screw by the screw-driver. 115

3. A machine of the class described including a rotary screw-driver and means for 120 rotarily actuating the same, in combination with means for magnetically holding a screw to be driven, said means being shiftable toward the screw-driver for driven engagement with the held screw by the screw-driver and comprising a magnet and a pair of 125 pole-pieces fixed to the poles of the magnet, the pole-pieces being magnetically spaced and insulated one from the other and co-op-

eratively shaped to provide a working aperture for the screw-driver and a seat for the screw-head.

4. A machine of the class described including a rotary screw-driver and means for rotarily actuating the same, in combination with means for magnetically engaging and holding a screw at its head, said means being apertured for accommodating driven engagement by the screw-driver with the screw.

5. A machine of the class described including a rotary shaft, a screw-driver carried for rotation by and with the shaft, and means for holding a screw to be driven in position for driving engagement by the screw-driver, in combination with means comprising a power-pulley loosely mounted on the shaft, and a clutch fixed on the shaft and normally in frictional engagement with the pulley for rotarily actuating the shaft and its carried screw-driver to seat the held screw in the work, the clutch being adapted to slip upon the pulley when the screw-driver is in engagement with the screw and the screw fully seated in the work.

to slip in its engagement with the pulley when the screw-driver is in engagement with the screw and the screw fully seated.

6. A machine of the class described including a rotary shaft, a screw-driver carried for rotation by and with the shaft, and means for holding a screw to be driven in position for driving engagement by the screw-driver, in combination with a power pulley loosely mounted on the shaft, a clutch member fixed on the shaft, and means comprising a spring for yieldingly holding the pulley and clutch in frictional engagement for rotarily actuating the shaft and its carried screw-driver to seat the held screw in the work, the clutch being adapted to slip upon the pulley when the screw-driver is in engagement with the screw and the screw fully seated in the work.

In testimony whereof, I have signed my name to this specification.

WILLIAM WURDACK.
